UNITED STATES PATENT OFFICE.

WILLIAM H. D. NEWTH, OF DETROIT, MICHIGAN.

LOCOMOTIVE ASH-PAN.

SPECIFICATION forming part of Letters Patent No. 298,350, dated February 12, 1884.

Application filed August 27, 1883. (No model.)

To all whom it may concern:

Be it known that I, WILLIAM H. D. NEWTH, of Detroit, in the county of Wayne and State of Michigan, have invented new and useful 5 Improvements in Locomotive Ash-Pans; and I do hereby declare that the following is a full, clear, and exact description thereof, reference being had to the accompanying drawings, which form a part of this specification. 10 This invention relates to certain new and useful improvements in the construction of that class of locomotive ash-pans by means of which the ashes and débris of the fire may be readily dumped at the will of the engineer from the cab, while at the same time the cab 15 may be air-tight.

The invention consists in the peculiar construction, operation, and combination of the parts, as more fully hereinafter described. 20 Figure 1 is a top perspective of my improved ash-pan, with a portion of the wall thereof broken out. Fig. 2 is a bottom perspective of the same. Fig. 3 is a vertical longitudinal section. Fig. 4 is a detached perspective of one of the slats.

In the accompanying drawings, which form a part of this specification, A represents the rear draft-door of the ash-pan, the front end of which is provided with a similar draft-door, A'. A ledge, B, is secured to the lower edge of each of the side walls of the ash-pan, and at suitable distances apart there are formed in the upper edges of these ledges recessed bearings a, to receive the pintles or 30 journals b of the slats or leaves B', which form the bottom of the ash-pan. Each end of the slats are centrally supported upon their bearings, and are so arranged that when 35 closed the forward edge of the one overlaps the rear edge of the next slat in front, which, when closed, forms a tight and flat bottom; or the same result is attained by casting the 40 rear edge of each slat with an offset. Near one end of each slat there is cast or otherwise rigidly secured an upwardly and forwardly projecting lug, c, and near the top of each of these lugs there is cast or otherwise 45 rigidly secured a pin, d, which engages with equidistant holes in the connecting-rod C, this 50 rod being only sufficiently long to make such

connections. The slat B'', which lies nearest the rear damper or forms the rear slat in the bed, is provided upon its lower side with two ribs, e, which perform the double function of stiffening the plate, and also the guards, to prevent the displacement of the bar D, which is secured to such slat between the ribs by means of bolts or rivets h. This bar may terminate, as in Fig. 1, at one end in a journal-bearing, i, which projects through a hole of the same 55 size in the side wall of the pan, and it is provided with a crank, g, by means of which and a suitable connecting-rod leading to the cab of the engine (not shown) the operator can readily dump the slats, leaving, when desired, no opening through which air can be 60 admitted to the ash-pan; but in Figs. 2 and 4 I show a preferable arrangement, in which I use a bar, D, securely attached to one of the slats, which is bent downwardly, so as to pass 65 below the edge of the ash-pan, and in this construction the necessity of forming a hole through the side of the pan is avoided, and it is therefore the preferable form.

In the winter season the slats B' are never 70 kept closed tight, as there is danger of their freezing together, and fire is liable to drop out between them. To obviate this, I cast or otherwise rigidly secure to the upper face of each 75 slat, and near the rear edge thereof, a flange, 80 J, which, when the slats are set slightly open, prevents the coals from rolling down and passing 85 between the slats.

I am aware that locomotive ash-pans with 90 slat bottoms adapted to be opened and closed are in use and have been patented, and hence I do not broadly claim an ash-pan with a slatted bottom.

What I do claim as my invention is—

A locomotive ash-pan the bottom of which 95 is formed with a series of dumping-slats inferiorly connected together, and adapted to be opened and closed from the cab of the engine, each slat being provided with a flange, J, upon its upper face, substantially as and for the purposes set forth.

WM. H. D. NEWTH.
